United States Patent Office

Des. 208,504
Patented Sept. 5, 1967

208,504

BOTTLE

Bertrand N. Trombley, Bloomfield Hills, Mich., assignor
to The Dow Chemical Company, Midland, Mich., a
corporation of Delaware

Filed June 10, 1966, Ser. No. 2,638

Term of patent 14 years

(Cl. D58—8)

FIGURE 1 is an elevational view of a bottle showing my new design;

FIGURE 2 is a top view thereof;

FIGURE 3 is a bottom view thereof, and

FIGURE 4 is an enlarged fragmentary elevational view of the ribbed neck portion thereof.

The dominant features of my design reside in the portions shown by full lines.

I claim:

The ornamental design for a bottle, as shown and described.
